NICHOLAUS SCHNUR, OF ELIZABETH, NEW JERSEY.

MACHINE FOR SHARPENING AND SIMILAR OPERATIONS.

1,170,116.

Specification of Letters Patent.

Patented Feb. 1, 1916.

Application filed November 20, 1915. Serial No. 62,452.

To all whom it may concern:

Be it known that I, NICHOLAUS SCHNUR, a citizen of the United States, and resident of Elizabeth, county of Union, and State of New Jersey, have invented certain new and useful Improvements in Machines for Sharpening and Similar Operations, of which the following is a specification.

This invention relates to a machine that is designed to be used for subjecting plates or sheets to abrasion or polishing by passing said plate or sheet over an element, and is particularly adapted for sharpening blades, this machine being of the type in which the sharpening device, so called in this specification for the purpose of identification, and the blade are supported in sliding relation so that one can be slid on the other.

The invention is designed particularly as a machine for sharpening razor blades, although it is adapted for sharpening other forms of blades, in fact it can be adapted for the purpose of polishing and in similar processes.

The machine is designed to be used as a honing machine for razor blades, and it is so described in this specification so as to make its operation clear, and it provides a holder for the blade and a holder for the hone, at least one of these being tilted so that the blade and the hone, by being pressed toward each other and having this tilting action, are forced to a position where the blade lies flat on the stone and the flat position is maintained during the whole travel of the blade along the hone so that an even edge is secured, which overcomes the unevenness in hand honing which is very often due to the operator unconsciously tilting the razor blade on the hone which, if done even to a slight extent, does not give as good a result as when the razor blade is held flat on the hone.

The machine is further designed to provide a blade holder which provides a side motion to the blade so that the blade travels diagonally on the hone, first one way and then the other, being turned over at the ends of the stroke and having means for preventing too rapid a reversal of the blade so that the edge of the blade comes down lightly on the hone and is not injured.

The form of machine shown in the drawings accompanying this specification is adapted for honing the ordinary type of razor, and has means for holding the handle

in an open position, but in a manner to permit its quick attachment or detachment.

The machine is also designed to be adjustable so that it can be used with hones of different lengths. The means for turning the blade and for providing the sliding motion are also adjustable for a long or short stroke as desired, according to the length of the hone.

The machine is illustrated in the accompanying drawings in which one embodiment of the invention is shown, which, however, can be altered to meet varying conditions, to receive different forms of plates or blades, and constructed with various combinations of parts to bring about the movements required in the manipulation of the blade.

In the drawings Figure 1 is a top view of the machine with the razor inserted in the holder provided for it, and Fig. 2 is an end view of the machine shown in Fig. 1. Fig. 3 is a detail view showing the front of the blade holder, the hone being illustrated in section. Fig. 4 is a section on line 4, 4 in Fig. 3. Fig. 5 is a detail view showing a device for maintaining the razor blade of an ordinary form of razor in position, and Fig. 6 is a side view of one of the abutments used to turn the blade holder over at the end of a stroke.

The machine that is illustrated consists of a base 10 which is of suitable form and may be provided, if desired, with the openings 11 to make it lighter in weight, and can be provided with suitable legs 12 for securing it to a table if necessary. The machine is provided with a blade holder and a hone that are in sliding relation and at least one of which can tilt, and one manner of providing this form of machine is illustrated in these drawings in which the hone 13 is preferably arranged within a case or box 14 which has, at its ends, projections such as the knife edges 15 which rest in the recess 16 of the standards 17. The standards are preferably fastened by means of screws 18 which screw into the table 10 and pass through slots 19 in the bottom part 20 of the standards 17. This provides for an adjustment of the hone toward and from the razor holder. Adjacent to and parallel with the hone is a rod 21 supported at its ends in suitable brackets 22. On the rod is a sleeve 23 which slides on the rod and is substantially T-shaped, having an arm 24 extending from it, the arm 24 having means thereon for holding a blade so that

the blade can be slid along the hone and also have a side motion, the preferred form of providing such motion being by arranging a slide 25 within a bore 26 of the arm 24.

5 The arm 24 is slotted above and below the bore, the upper slot 27 receiving the neck 28 of a carriage 29, the carriage having bearings 30 on its ends, these bearings carrying a rod 31 which is adapted to oscillate in the

10 bearings 30, the forward end of the rod being provided with a suitable clamp 32, this clamp having a recess 33 to receive the tang 34 of a razor, the blade 35 of the razor resting on the hone. The tang is secured in any

15 suitable way, in the drawing a screw 36 being shown as the medium for holding the tang 34 in place.

The forward and outer edges of the clamp 32 are rounded on both the top and bottom 20 faces as at 37 and 38 to provide bearing surfaces for engaging the curved inner faces 39 of the abutments 40, these abutments being fastened, by means of their bottom plates 41, to the base 10 of the machine, this 25 being usually done by screws 42 fitting in the slots 43 of the bottom plates 41. The slotted connection provides one means for adjusting the abutments toward and from each other so as to regulate the place where 30 the blade will be turned over, this turning operation being described hereinafter.

The slide 25 is provided with a recess into which the head 44 of a post 45 fits, the head 44 being usually made so that it springs into 35 place and can be removed by giving it a positive jerk, the post projecting through the lower slot 46 in the arm 24. The post 45 is arranged on the end of a spring arm 47 which swings on the pivot 48, the outer end 40 49, to which the post 45 is secured, having a constant tendency to spring upward so that it holds the arm 24 up and yieldingly presses upward so as to force the sleeve 23 to turn on the rod 21 to force the blade 35 45 of the razor on the hone. It will be evident that other means of sliding and pressing on the blade holder can be used, but the spring arm 47 is simple and provides the necessary side motion to the razor blade holder and 50 also propels the blade holder along the rod 21. One manner of reciprocating the spring arm 47 is by means of a swiveled stud 49 which receives the end of a connecting rod 50 which has, at its end, an eye 51 fitting 55 on the right-angled end 52 of a crank 53. The crank 53 slides through the end of the shaft 54 and is adjustable therein, being held in desired positions by means of a suitable set screw 55. In this way the throw of 60 the crank 53 can be regulated. The shaft 54 is mounted in a bearing 54^a and is provided with a suitable operating means, in the form shown this being hand means and comprising a wheel 56 against which a plate 57 is 65 placed, the plate 57 having slots 58 and 59

passing over the stud 60 and the clamping screw 61, so that the throw of the handle 62 can be regulated.

In sharpening an ordinary razor the handle 63 must be secured in place, and to 70 provide a ready and quick means of attaching and detaching it, I arrange a spring loop 64 over which the two sides of the handle 63 are passed, the loop being preferably made from a sheet of metal, which sheet passes 75 through the end of the rod 31 and is thus held in place and has, on its opposite side, a fan or wing 65. It will be evident that when the handle 62 is turned the connecting mechanism causes the spring arm 47 to reciprocate on its pivot 48, and since the 80 spring arm 47 also causes the razor blade to be pressed down against the hone, the blade holder is moved so that the sleeve 23 thereof slides along the rod 21 and at the 85 same time the carriage 29 slides on the arm 24 and the razor is thus given two motions, namely, it passes edge first along the hone and at the same time is given the side motion due to the fact that the hone is straight, 90 and the spring arm 47 swinging on the pivot 48, describes, with its end, the arc of a circle. This path of travel of the end of the spring arm causes the carriage 29 to be carried backward and forward on the arm 24 as 95 the arm is slid. When the blade holder gets near the end of a stroke, the clamp 32 is engaged at one of its curved faces 37 with the inner face 39 of one of the abutments 40, and it is turned over, the back of the blade 100 resting on the hone during the turning movement. The weight of the clamp 32, which is rather heavy, assists in causing the continued turning of the blade holder, after it has passed beyond the vertical, through 105 its engagement with the abutment 40, but any excessive dropping of the blade is prevented by reason of the wing or fan 65 which provides a wind or air resistance just sufficient to permit the razor blade to be deposited lightly against the hone in beginning its return stroke. This reversal of the blade takes place at the end of each stroke, 110 as will be evident, and a constant honing is possible, the turning of the blade being automatic and gentle, the blade being slid in two directions as above described, that is, having a side motion in addition to its motion longitudinally of the hone, and the tilting hone is acted upon by the blade so 115 that the blade and the hone lie so that the edge of the blade is parallel with the surface of the hone, and this even contact is maintained for the full length of travel of the blade. I have found that this machine provides a good edge on a razor blade, does it 120 quickly and is inexpensive both to make and maintain.

It will be evident that modifications can be incorporated in the machine to vary the 125 130

shape and disposition of the various parts, and while a sharpening process is described in this specification, the machine can be used for grinding or polishing articles, and 5 while in this specification and claims the hone is broadly termed a "sharpening element" it may be a polishing or abrading surface.

Having thus described my invention, I 10 claim:

1. A sharpening machine comprising a hone mounted so that it can tilt, an arm 15 slidably supported adjacent to the hone, a carriage sliding on the arm, a spring arm swinging on one end and having its other 20 end pivotally attached to the carriage, means for oscillating the spring arm, and means on the carriage for holding a blade.

2. A sharpening machine comprising a 25 hone mounted so that it can tilt, an arm slidably supported adjacent to the hone, a carriage sliding on the arm, a spring arm swinging on one end and having its other end pivotally attached to the carriage, means for oscillating the spring arm, means 30 on the carriage for holding a blade, and abutments against which the blade holding means are pressed at the end of each stroke of the arm to turn the blade holder.

3. A sharpening machine comprising a 35 hone, an arm sliding adjacent to the hone, a carriage on the arm, a spring arm adapted to swing at one end and having its other end pivotally connected to the carriage, a pivoted blade holder on the carriage, means 40 on the blade holder for securing a blade in position thereon, abutments against which the blade holder is forced at the ends of the strokes to turn the blade holder, and means 45 for adjustably securing said abutments toward and from each other.

4. A sharpening machine comprising a hone, an arm sliding adjacent to the hone, a carriage on the arm, a spring arm adapted to swing at one end and having its other 45 end pivotally connected to the carriage, a pivoted blade holder on the carriage, means on the blade holder for securing a blade in position thereon, abutments against which the blade holder is forced at the ends of the 50 strokes to turn the blade holder, means for adjustably securing said abutments toward and from each other, and a wing on the blade holder to provide resistance against the turning of the blade holder. 55

5. A sharpening machine comprising a hone, means for supporting the hone so that it can tilt, a rod adjacent to the hone, a sleeve having an arm thereon, the sleeve being rotatable and slid able on the rod, a carriage slid able in the hone in a direction transverse to the sliding movement of the arm, a blade holder on the carriage, means on the blade holder for holding a blade, a wing on the blade holder having a projecting loop thereon, the blade holder having rounded edges, abutments in the path of said rounded edges to turn the blade holder at the ends of the strokes, means for adjustably securing the abutments so that they 60 can be moved toward and from each other, a spring arm pivoted at one end so that it can swing and having its free end pivoted to the carriage, the arm having a tendency 65 to force the carriage to cause a blade held in the holder to engage the hone, and means for swinging the spring arm. 70

In testimony that I claim the foregoing, I hereunto set my hand, this 18th day of November, 1915.

NICHOLAUS SCHNUR.
